(57) **CLAIM**

The ornamental design for a table, as shown and described.

DESCRIPTION

FIG. 1 is a front, top perspective view of a table showing my new design;

FIG. 2 is a rear, bottom perspective view thereof;

FIG. 3 is a top plan view thereof;

FIG. 4 is a bottom plan view thereof;

FIG. 5 is a side elevational view thereof, the opposite side being a mirror image; and,

FIG. 6 is a front elevational view thereof, the rear elevational view being a mirror image.

The drawings show a table design having a transparent or translucent, an opaque, textured horizontal surfaced under the top, and transparent or translucent leg structures. The wide dashed lines throughout the figures represent the perimeter of the table top and outline shape of the support leg structures and form no part of the claimed invention.
